(57) **CLAIM**

The ornamental design for a handheld spray nozzle, as shown and described.

DESCRIPTION

FIG. 1 is a front, right, top perspective view of a handheld spray nozzle, showing my new design;

FIG. 2 is a rear, left, bottom perspective view of the reduced scale thereof;

FIG. 3 is a front elevational view of the enlarged scale thereof;

FIG. 4 is a rear elevational view of the enlarged scale thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 2;

FIG. 13 is an enlarged view of detail 13 in FIG. 2;

FIG. 14 is an enlarged view of detail 14 in FIG. 2;

FIG. 15 is an enlarged view of detail 15 in FIG. 3;

FIG. 16 is an enlarged view of detail 16 in FIG. 3;

FIG. 17 is an enlarged view of detail 17 in FIG. 3;

FIG. 18 is an enlarged view of detail 18 in FIG. 4;

FIG. 19 is an enlarged view of detail 19 in FIG. 4;

FIG. 20 is an enlarged view of detail 20 in FIG. 4;

FIG. 21 is an enlarged view of detail 21 in FIG. 5;

FIG. 22 is an enlarged view of detail 22 in FIG. 5;

FIG. 23 is an enlarged view of detail 23 in FIG. 6;

FIG. 24 is an enlarged view of detail 24 in FIG. 7;

FIG. 25 is an enlarged view of detail 25 in FIG. 7;

FIG. 26 is an enlarged view of detail 26 in FIG. 8; and,

FIG. 27 is an enlarged view of detail 27 in FIG. 8.

The dashed broken lines in the figures are for the purposes

of illustrating portions of the handheld spray nozzle and

form no part of the claimed design.

The dash broken lines with longer segments in the figures

are for the purposes of illustrating the boundaries of the

detail enlargements that form no part of the claimed design.
